UNITED STATES PATENT OFFICE.

GEORGE T. PENLAND, OF GASTONIA, NORTH CAROLINA.

TENSION DEVICE.

1,399,649.

Specification of Letters Patent.

Patented Dec. 6, 1921.

Application filed January 14, 1921. Serial No. 437,330.

To all whom it may concern:

Be it known that I, GEORGE T. PENLAND, a citizen of the United States, residing at Gastonia, in the county of Gaston and State 5 of North Carolina, have invented new and useful Improvements in Tension Devices, of which the following is a specification.

The object of my present invention is the provision of a highly efficient tension device 10 designed more especially, though not necessarily, for use in cotton yarn spoolers or winders.

A peculiar and desirable characteristic of 15 the device resides in the fact that by virtue of the construction of the device an operator can tie the ends of yarn sections above the device and release the yarn whereupon the yarn will be guided to proper working position in the device.

20 To the attainment of the foregoing, the invention consists in the improvement as hereinafter described and definitely claimed.

In the accompanying drawings, forming part hereof:—

25 Figure 1 is a plan view of the tensioning device constituting the best practical embodiment of my invention that I have as yet devised, the course of the yarn through the device being indicated by dotted line.

30 Fig. 2 is a front elevation of the device.

Fig. 3 is a transverse section taken in the plane indicated by the line 3—3 of Fig. 1, looking toward the left.

35 Fig. 4 is an elevation of the left hand end of the device.

Fig. 5 is an elevation of the right hand end of the device.

Fig. 6 is an inverted plan of the rotary gravitational friction member of the device.

40 Fig. 7 is a fragmentary plan of that portion of the body plate of the device over which the friction member operates.

Similar numerals of reference designate corresponding parts in all of the views of 45 the drawings.

Among other elements my novel device comprises a body plate 1 which is preferably of metal. The said body plate 1 is provided at its right hand rear corner with 50 a clamp 2 through the medium of which it is affixed on the usual transverse rod (not shown) of a spooler or winder. It will also be noticed by comparison of the several figures that the body plate 1 is characterized 55 by a mouth 3 which reaches inwardly from the left hand end of the plate and is tapered

to a narrow slot 4 which, in turn, merges into an eye 5; the said slot 4 and eye 5 being designed to rest under the rotary friction member hereinafter described. The body 60 plate 1 is further characterized by an elongated opening 6 for the downward escape of litter or lint, and by an upwardly reaching longitudinal lip 7 that is positioned in rear of the opening 6 and is provided with a 65 sharp edge 8 and with a rounded rear side 9. Rising from the rear edge of the body plate 1 is a preferably integral standard 10, said standard being located adjacent to the left hand edge of the lip 7. The body plate 70 1 also carries a post 11 located as illustrated adjacent to the slot 4 and the eye 5.

In addition to the body plate 1 characterized as described the tension device comprises a combined guard and guide 12 and 75 a rotary friction member 13. The combination guard and guide is preferably formed in one piece of metal, and is made up of an upright 14 which is connected to and rising from the body plate 1 at the rear side of 80 the mouth 3. At its upper end the said upright 14 is merged into an inclined portion 15 which is carried downwardly to a point adjacent to the upper side of the body plate 1 and is there merged into a transverse and 85 comparatively thick portion 16 which extends at right angles across the opening 6 and has its lower edge spaced from the upper side of the body plate 1 as best shown in Fig. 3. The said transverse portion 16 90 is merged, in turn, into a comparatively wide arm 17. This arm 17 is disposed in front of the standard 10, is slotted at 18 to receive a screw 19 by which it is adjustably connected to the standard, and terminates 95 at its end in a flange 20 that abuts against the left hand edge of the standard 10. Manifestly the combination guard and guide is capable of being adjusted so as to position the lower edge of its arm 17 a greater 100 or less distance above the sharp edge 8 of the lip 7 to suit yarn of different sizes.

The rotary friction member is numbered 13. It is mounted on the post 11 so as to be freely revoluble about the same, and is 105 provided in its underside with kerfs 22 which are designed incident to the turning of the friction member to clear lint or litter from beneath itself.

In Fig. 1 I show by dotted lines the course 110 of yarn through my novel tension device which is located between the usual spindle

and spool of a spooler or winder. In this connection it will be noticed that the yarn is adequately tensioned, and it will also be noticed that by virtue of the yarn being carried over the sharp edge 8 of the lip 7 and under the edge of the guard arm 17, any knots or enlargements in the yarn will be either reduced, or the yarn will be cut or broken at such point whereupon it will be the province of an attendant to tie the ends of the yarn sections together. At this point I would direct attention to the fact that by reason of the construction of my tension device it is feasible for the attendant to tie the ends of the yarn sections at a point above the tension device and then release the yarn, when due to the action of the combination guard and guide the yarn will correctly find its way through the tension device.

The combination guard and guide is so designated inasmuch as it is adapted to prevent a falling spool from interfering with the friction member or the yarn *en route* through the device.

My novel tension device has been successfully used in actual practice, and has demonstrated a high degree of utility in connection with the operation of a spooler or winder.

Having described my invention, what I claim and desire to secure by Letters-Patent, is:—

1. The combination in a tension device, of a body having a mouth and an eye connected by a slot with the mouth, a friction member

on the body and above said slot and eye, and a guide arranged to guide yarn to the eye and under the friction member and having a portion opposed to and spaced from a portion of the body to stop knots. 40

2. In a tension device the combination of a body having an inwardly tapered mouth and an eye connected through a slot with the inner end of said mouth and also having on its rear portion a lip with a sharp edge, 45 a guard and guide having an upright portion connected to the body and also having a forward inclined portion, a transverse portion and a rear arm connected with the body, and a rotary friction member mounted on the body and disposed above the slot and eye. 50

3. In a tension device the combination of a body having an inwardly tapered mouth and an eye connected through a slot with 55 the inner end of said mouth and also having on its rear portion a lip with a sharp edge, a guard and guide having an upright portion connected to the body and also having a forward inclined portion, a transverse 60 portion and a rear arm connected with the body, and a rotary friction member mounted on the body and disposed above the slot and eye; the said body being adapted for connection to a carrying rod and being further provided in front of the lip with a litter-discharge opening. 65

In testimony whereof I affix my signature,

GEORGE T. PENLAND.
